HANS KNUDSEN, OF NORTH WINDSOR, WISCONSIN.

Letters Patent No. 95,591, dated October 5, 1869.

IMPROVEMENT IN STEAM-ENGINE SLIDE-VALVES.

The Schedule referred to in these Letters Patent and making part of the same.

To all whom it may concern:

Be it known that I, HANS KNUDSEN, of the city of North Windsor, county of Dane, and in the State of Wisconsin, have invented a new and useful Improvement in Slide-Valves for Steam-Engines; and I do hereby declare that the following is a full, clear, and exact description thereof, reference being had to the accompanying drawings, making part of this specification, in which—

Figure 1 is a side elevation of a steam-engine with my improvements attached.

Figure 2, a plan or top view of the same.

Figure 3, a longitudinal section of the cylinder, showing the construction of the slide-valve, and the arrangement of the steam-passages.

Figure 4 is a similar section.

Figure 5 is a similar view as fig. 2, the valves being removed from the boiler and cylinder, to show the arrangement of the ports.

Figure 6 is a bottom view of the cylinder slide-valve.

Figure 7 is a longitudinal section of the boiler slide-valve, showing the arrangement of the ports and passages.

Figure 8 is a similar section, showing the valve in a different position.

Figure 9 is a bottom view of the boiler slide-valve.

Figure 10 is a longitudinal section of the same.

Corresponding letters refer to corresponding parts in the several figures.

My invention relates to oscillating steam-engines, and may be portable; and

It consists in the construction and arrangement of the valves, as hereinafter more fully described.

To enable those skilled in the art to make and use my invention, I will proceed to describe its construction and operation.

A represents the cylinder, mounted upon trunnions, through which steam is admitted, at their centres, to and exhausted from the cylinder.

B represents the seat of the slide-valve, which is secured to the boiler W, in such a manner that its ports b^i and b^{ii} are directly over two ports in the boiler.

Its passages b^i and b^{iii} connect, respectively, with the pipes E and E', which lead to and connect with the trunnions of the cylinder, while its passage b^{ii} connects with the exhaust-pipe D.

C represents the boiler slide-valve, which is placed upon its seat B, and held thereto by means of a strap, C', and thumb-screws.

Its recesses c and c' are of such dimensions that each spans two apertures of the seat; thus, in fig. 7, the recess c spans the port b and passage b^i , and admits steam to the cylinder through the pipe E, while the recess c' spans the passages b^{iii} and b^{ii} , opening a

passage for the exhaust-steam, which escapes from the cylinder, through pipe E', and, by means of the valve C, through the exhaust-pipe D.

In this position of the valve, the port b^i is closed.

The boiler slide-valve, above described, is used as an induction and education-valve, and also for reversing the engine, and its operation is as follows:

When it is in the position shown in fig. 7 of the drawings, relatively to the ports and passages beneath, steam is admitted through the pipe E, and exhausted through the pipe E'.

If it is now shifted to the position shown in fig. 8, the exhaust-pipe becomes the induction-pipe, and the motion of the engine is reversed.

F represents the upper partition of the cylinder, having the ports f and f^i , through which the steam passes into and out of the cylinder, and the passages f^{ii} and f^{iv} , which unite in the trunnion, and connect with the pipe E, and the passage f^3 connecting, through the opposite trunnion, with the pipe E'.

H represents the slide-valve, which is placed upon and covers the ports and passages of the cylinder, and has, across its centre, a shaft or journal, I, the ends of which rest in bearings on the upper part of the standards supporting the cylinder.

The upper wall of this valve is cast hollow, thus forming a connecting passage between its ports h^{iii} , h , and h^i , as shown in figs. 3 and 4.

It is provided, at its under surfaces, with recesses h^{ii} and h^{iv} , which, at the proper time, connect the relative ports and passages of the cylinder.

On top of this valve is placed a plate, H', secured, by means of straps H'', to the cylinder, and adjusted by means of thumb-screws, passing through the tops of the straps, and bearing upon said plate, or, to reduce friction, rollers may be made to bear upon the valve, and hold it firmly and steam-tight to the cylinder.

By these devices, the oscillation of the cylinder beneath the valve, causes a relative change of the position of the two, sufficient to open and close the proper ports at the proper time.

It will be seen that by the above-described construction of the valve, steam may be admitted through the pipe E, from which it passes into the passage f^3 of the cylinder, and up through the ports h^{iii} of the valve, to each end of the cylinder alternately, as communication is opened with its port. In this event, the exhaust steam passes under the recesses of the valve into the branched passage of the cylinder, and through the pipe E; or the pipe E may be used as the education-pipe, when the steam is admitted through the branched passage of the cylinder, and passes under the recesses of the valve alternately, to each end of the same, and in this event, the exhaust steam escapes through the passage of the valve into the pipe E'.

Valve H may be employed on stationary as well as on oscillating machines.

Having thus described my invention,

What I claim, and desire to secure by Letters Patent, is—

1. The arrangement of the valve H, having the journal I, the plate H¹, and straps H², substantially as shown and described.

2. The construction and arrangement of the valve C and its seat B, in relation to the induction and

eduction-pipes E and E', and the valve H of the cylinder A, substantially as described.

In testimony whereof, I have signed my name to this specification, in the presence of two subscribing witnesses.

HANS KNUDSEN.
